TO THE BRIDGEPORT METAL GOODS MANUFACTURING COMPANY, OF BRIDGEPORT,
CONNECTICUT, A CORPORATION OF CONNECTICUT

LIP STICK CONTAINER

Application filed April 8, 1931. Serial No. 528,466.

This invention relates to new and useful improvements in lipstick containers or holders of the type including a carrier and means to move the carrier to project and retract a 5 lipstick supported by the carrier.

An object of the invention is to provide a 10 lipstick container including an improved construction and arrangement of parts whereby the parts may be made at low cost and easily 15 assembled to produce a container or holder at a relatively low cost.

Another object is to provide a lipstick container of neat and attractive appearance and 20 which is easy to operate to project or withdraw the lipstick and which includes a minimum number of parts.

Other objects and advantages will become 25 apparent from a consideration of the following detailed description taken in connection with the accompanying drawing. However, it is to be understood that the invention is not limited to the details shown and described but includes such variations and modifications as fall within the spirit of the invention and the scope of the appended claims to which claims reference is to be had for a definition of the invention.

In the drawing: 30 Fig. 1 is a partial side elevation and partial section of the device in the closed position;

Fig. 2 is a transverse sectional view on the line 2—2 of Fig. 1;

Fig. 3 is a side elevational view of the outer 35 casing;

Fig. 4 is a top plan view of the casing of Fig. 3;

Fig. 5 is a side elevational view of the inner 40 rotary sleeve;

Fig. 6 is a top plan view of the sleeve of Fig. 5;

Fig. 7 is a side elevational view of the carrier;

Fig. 8 is a sectional view on the line 8—8 45 of Fig. 7; and

Fig. 9 is a plan view of the carrier.

Referring in detail to the drawing, the improved lipstick container as illustrated comprises an outer tubular shell 10 open at its 50 opposite ends and preferably with its upper end inturned somewhat as shown at 11 to

facilitate the application of the cap 12. At a suitable distance from the inturned end 11 the casing 10 is provided with an outwardly extending bead 13 to be engaged by the end of the cap 12 and form a stop to limit movement of the cap. 55

A portion of the wall of the casing 10 is pressed outwardly to provide a spiral guideway 14 opening through the inner surface of said wall. The function of this guideway will later be fully set forth, but here it may be stated that in ornamenting the outer casing the spiral 14 may also play an important part. For example, the casing with the exception of the spiral guideway 14 may be painted or enameled or ornamented in one color and the spiral may be covered with a material of contrasting color. For example, the body may be red while the spiral is gold. It will be noted that the spiral opens through one end of the casing 10 as at 15 and that the other end of the spiral stops at or is limited by the bead 13. 60 65 70 75

The feeding means or the means for propelling the lipstick to have it project beyond the casing for use or to withdraw it into the casing includes a rotary sleeve 16 in the form of a tube closed at its lower or inner end as by a head 17 of a diameter greater than the diameter of sleeve 16 and casing 10 whereby 80 to project as shown in Fig. 1 for convenient manipulation. If desired the head 17 may be knurled or otherwise treated whereby to afford a better grip. 85

Sleeve 16 has a longitudinally extending slot 18 which slot is closed at its opposite ends as clearly shown in Fig. 5 and this slot is adapted to cooperate with the spiral guideway 14 and a guide pin (which guide pin will later be described) to shift the lipstick longitudinally in the casing 10. Also, the sleeve 16 is slotted or split as at 19, the slots 19 opening through the outer or upper end of the sleeve whereby to make this end portion of the sleeve more or less resilient in that its portions at opposite sides of the slots 19 may be pressed toward one another. While two slots 19 are shown and while these slots are shown as arranged at diametrically opposite 90 95 100 points it will be understood that more or less

slots may be provided and that other arrangements of the slots may be used.

The upper or outer end portion of the sleeve 16 is turned outwardly as at 20 to provide a lip or flange. The sleeve 16 is of such diameter as to nicely fit within the casing 10 and turn evenly and smoothly, and the sleeve is to be inserted through the lower or inner end of the casing. Owing to the presence of the lip or flange it is necessary to compress the upper or outer end portion of the sleeve in order to insert it in the casing 10 and such compression may take place owing to the slots 19. When the sleeve is inserted in the casing to the proper distance the outward portion or lip or flange 20 of the sleeve springs into the groove formed at the inner side of the bead 13 and serves to yieldingly secure the sleeve in the casing. However, since this groove at the inner side of bead 13 is circular it will be understood that the sleeve may be rotated in the casing the frictional contact between the sleeve and casing being such as to prevent casual movement of the sleeve out of the casing and such that the sleeve may be rotated with a smooth movement relative to the casing.

Within the rotary sleeve 16 and movable longitudinally therein is a carrier 21 for the lipstick. This carrier is of general tubular shape open at its upper end to receive the lower or inner end of the lipstick while its lower end is partially closed by wall 22 providing a small opening 23, the wall 22 serving to prevent the pushing of the lipstick through the carrier should the lipstick be forced too far into the carrier. A pin 24 movable with the carrier 21 has an end 25 projecting beyond the wall of the carrier and through the slot 18 in the sleeve 16 and into the spiral guideway 14 of the casing 10. Therefore, by relative rotation between the sleeve 16 and the casing 10 the projecting end 25 of the pin moves along the slot 18 and the spiral guideway 14 due to the camming action created and slides the carrier 21 and the lipstick therein, longitudinally of the sleeve and casing to either project the lipstick from the casing for use or to retract it into the casing.

Carrier 21 has spaced inwardly extending beads 26 and 27 and just above the bead 27 the carrier is pierced as indicated at 28 and the walls of the carrier about the opening 55 are drawn inwardly somewhat as at 29. The opening 28 is somewhat smaller in diameter than the pin 24 and therefore when the pin is forced into the opening the side walls 29 are expanded giving a firm grip on the pin. Preferably pin 24 is of such length that its inner end engages the opposite inner surface of the carrier or is disposed closely adjacent said surface just above the bead 27 as shown in Fig. 8.

It will now be apparent that the operation

of assembling the pin 24 in the carrier 21 merely involves forcing the pin inwardly through the opening 28 until the inner end of the pin is stopped by the wall of the carrier opposite the opening. The end portion 25 of the pin will then project from the carrier the proper distance to pass through the slot 18 of the sleeve 16 and into the spiral guideway 14 of the casing 10. The pin is thoroughly supported by the walls about the pierced opening 28 and the inner end of the pin is supported by the bead 27 so that said inner end cannot be forced downwardly out of position should the lipstick be inserted too far into the carrier. Further, the bead 26 will serve as an additional means for securing the lipstick in the carrier.

In assembling the improved device the carrier 21 is first assembled in the sleeve 16 with the pin 24 having its end portion 25 extending through the slot 18 in the sleeve. The end portions of the sleeve are next compressed toward one another as provided for by the slots 19 and as the sleeve is inserted and pushed into the casing the sleeve is turned to dispose the projecting end portion 25 of the pin 24 to enter the lower end of the spiral guideway 14 at 15.

After the parts are assembled the sleeve 16 turns smoothly in the casing to feed the carrier 21 outwardly or inwardly to project or retract the lipstick. However, the connection provided by the lip or flange 20 of the sleeve entering the groove at the inner side of the bead 13 is such that the camming action of the pin in the guideway 14 acts to move the carrier and not to force the sleeve 16 out of the casing. A good strong pull on the head 17 will serve to withdraw the sleeve from the casing. The spring action of the slotted end of the tube 16 causes it to frictionally engage the inner surface of the casing so that although the tube turns smoothly in the casing to project or retract the lipstick this friction is sufficient to hold it in adjusted positions under ordinary use. That is this friction is sufficient so that the pressure on the projected end of the lipstick incident to use will not force it back into the casing, but it will remain in adjusted position until shifted by turning of the inner sleeve.

From the foregoing description it will be understood that the lipstick container of the present invention is extremely simple in construction and involves but a few parts. In this connection it will be noted that the casing 10 being provided with the spiral guideway 14 serves not only as a casing but as part of the propelling mechanism for imparting movement to the carrier. It will also be noted that the parts are easily and quickly assembled without the use of rivets or other securing means.

Having thus set forth the nature of our invention, what we claim is:

1. In a lipstick container, an outer cylindrical casing, said casing having a spiral guideway, said casing having an outwardly pressed bead forming a groove in its inner 5 surface, said bead serving to limit movement of a cap onto said casing, a rotary sleeve in said casing and having a longitudinal slot through its wall, said sleeve split longitudinally for a portion of its length beginning at 10 its inner end whereby said end portion is resilient, said sleeve having said end out-turned to form a flange adapted to enter the groove in the casing to yieldingly secure the sleeve in the casing, and a carrier in the sleeve and having 15 a projection extending through said slot and engaging said guideway whereby the carrier will be moved longitudinally of the sleeve on relative turning movement between the sleeve and casing.
2. In a lipstick container, an outer cylindrical casing, said casing having a spiral guideway, said casing having an outwardly pressed bead forming a groove in its inner 20 surface, said bead serving to limit movement of a cap onto said casing, a rotary sleeve in said casing and having a longitudinal slot through its wall, said sleeve having a resilient inner end portion, said sleeve having a flange on said portion and adapted to enter the 25 groove in the casing to yieldingly secure the sleeve in the casing, and a carrier in the sleeve and having a projection extending through said slot and engaging said guideway whereby the carrier will be moved longitudinally of the 30 sleeve on relative turning movement between the sleeve and casing.
- 35

In testimony whereof we affix our signatures.
